UNITED STATES PATENT OFFICE.

GARDNER W. BAKER, OF PAINESVILLE, OHIO.

CLAMP.

SPECIFICATION forming part of Letters Patent No. 417,307, dated December 17, 1889.

Application filed April 26, 1889. Serial No. 308,678. (No model.)

To all whom it may concern:

Be it known that I, GARDNER W. BAKER, of Painesville, in the county of Lake and State³ of Ohio, have invented certain new and useful Improvements in Clamps; and I do hereby declare the following to be a full, clear, and exact description of the invention, such as will enable others skilled in the art to which it pertains to make and use the same.

10 My invention relates to improvements in clamps; and it consists in certain features of construction and in combination of parts hereinafter described, and pointed out in the claims.

15 In the accompanying drawings, Figure 1 is a side elevation. Fig. 2 is an elevation in longitudinal section. Figs. 3 and 4 are end elevations showing the inner faces of the two members of the clamp.

20 Heretofore light portable clamps have usually been constructed with sockets to fit a bar of wood or metal, and consequently such tie-bar was usually carried about with the clamps in the tool-chest, and frequently such 25 tie-bar was not long enough for the work in hand. I have therefore devised clamps adapted to be placed on, for instance, the edge of a board or any strip of wood at hand to serve as a tie-bar, and consequently such tie-bar 30 has not to be carried about. The two members of the clamp A and B are similar in construction, except the former has a flat face-

35 plate a for engaging the work, and member B has a thumb-screw b for the same purpose, such thumb-screw being provided with a broad-faced cap b'. Face-plate a is set at right angles to the member a', the latter having a flat surface for engaging the edge of the wooden board or strip C, that serves as a tie-

40 bar. The rear end of member a' is provided with a depending V-shaped rib a². When a pressure is applied to face-plate a in clamping the work, rib a² is pressed down and made to indent the wooden strip C to prevent the 45 clamp from slipping. Members a a' are braced by a broad thin web a³. A' A² are opposing jaws depending from the body of the clamp and adapted to extend down astride the tie-bar C. Jaw A' has a lateral screw-threaded

hole for receiving thumb-screw D for tightening the member of the clamp upon the tie-bar. These two jaws are re-enforced by a broad thin curved flange A³, the form thereof being shown more clearly in Figs. 3 and 4. Jaw A² has a circular V-shaped rib A⁴ projecting from the inner face thereof, this rib being located opposite screw D. In tightening screw D rib A⁴ is pressed into the wood and helps to hold the clamp from slipping. Member B, except its being provided with screw-threaded hole for receiving screw b aforesaid, is constructed substantially the same as member A, and therefore need not be described in detail. Such clamps for light work may be of such comparatively small size 65 that the workman can carry them in his pocket, and yet these clamps can be made to stand work of any size, the only limit in this respect being the length of the tie bar or board C, to which, for the time being, the clamp may 70 be secured. By reason of the thin broad web and flange, respectively, a³ and A³, the necessary strength is secured with but little weight of metal, and clamps of such construction and for light work need not weigh but a few ounces. 75 The two members of the clamp are usually constructed right and left handed, as shown, so as to bring the securing thumb-screws D on the same side of the clamp, although this is not a matter of importance. 80

What I claim is—

1. Clamps, the one member thereof having a flat bearing, a rigid face-plate integral therewith and projecting from one side at right angles thereto, the other member having a flat bearing, a rigid face-plate, a thumb-screw mounted in the rigid plate for engaging the work, each member having jaws projecting from the flat bearing on the side opposite the face-plates, and thumb-screws for locking the 85 clamps to a tie-bar, substantially as set forth. 90

2. Clamps, the one member thereof having a flat bearing, a rigid face-plate integral therewith and projecting from one side at right angles thereto, the other member having a flat bearing, a rigid face-plate, and a thumb-screw mounted in the rigid face-plate for engaging the work, each member having jaws project- 95

ing from the flat bearing on the side opposite the face-plate, thumb-screws for locking the clamps to a tie-bar, and the ribs a^2 A^4 , substantially as set forth.

5 3. Clamps consisting, essentially, of members a a' , constructed at right angles to each other, rib a^2 , jaws A' A^2 , and flange A^3 , the parts being integral, substantially as set forth.

In testimony whereof I sign this specification, in the presence of two witnesses, this 10th day of March, 1889.

GARDNER W. BAKER.
